CHRISTMAS TREE LIGHT HOLDING BRACKET

John P. Garver, near Poland, Ohio
(9450 Sharrott Road, Poland, Ohio)

Filed May 19, 1964, Ser. No. 80,055

Term of patent 3½ years

(Cl. D17—12)

FIGURE 1 is a front elevational view of a Christmas tree light holding bracket, showing my new design wherein the open loop is curved;

FIGURE 2 is a side elevational view thereof;

FIGURE 3 is a front elevational view of a modified form of the Christmas tree light holding bracket of my new design wherein the open loop is angular;

FIGURE 4 is a side elevational view thereof.

The side opposite each side shown is a mirror image of the side shown.

I claim:

The ornamental design for a Christmas tree light holding bracket, as shown and described.
